UNITED STATES PATENT OFFICE.

WALTER SIMPSON FINCH, OF GREENVILLE, SOUTH CAROLINA.

PICKER-STICK CHECK FOR LOOMS.

1,255,830.

Specification of Letters Patent. Patented Feb. 5, 1918.

Application filed April 30, 1917. Serial No. 165,539.

To all whom it may concern:

Be it known that I, WALTER S. FINCH, a citizen of the United States, residing at Greenville, in the county of Greenville, State 5 of South Carolina, have invented a new and useful Picker-Stick Check for Looms; and I do hereby declare the following to be a full, clear, and exact description of the invention, such as will enable others skilled in the art 10 to which it appertains to make and use the same.

This invention relates to an improved picker-stick check for looms, and an object of 15 the same is the production of a device of this kind, whereby the picker stick, when subjected to the impact of the shuttle, in its outward movement is checked.

A further object of the invention is to provide a simple, efficient and very durable 20 device of this kind, which will outlast the old style of leather check strap, such as is used on "Draper" looms.

A further object is to provide a device of 25 this kind which will avoid successive repairs, as well as saving time that is wasted in making repairs.

The invention comprises further features and combination of parts hereinafter set forth, shown in the drawings and claimed.

30 In practical fields the details of construction may require alterations falling within the scope of what is claimed.

In the drawings:—

Figure 1 is a front elevation of a portion 35 of a picking mechanism at one side of a loom, showing the improved picker-stick check as applied thereto.

Fig. 2 is a view in side elevation disclosing the opposite side to that shown in 40 Fig. 1.

Fig. 3 is a sectional view on line 3—3 of Fig. 1.

Fig. 4 is an enlarged detail perspective 45 view of the picker-stick check mechanism detached.

Fig. 5 is a sectional view on line 5—5 of Fig. 4.

Fig. 6 is a sectional view on line 6—6 of Fig. 4.

50 Referring more especially to the drawings, 1 designates a portion of one side of a loom, and 2 the lay rocker-shaft having fast thereon the picker-stick stand 3, and 4 denotes the picker-stick. Projecting laterally 55 from the picker-stick stand 3 and downwardly is an arm 5, and arranged in an

opening 6 of said arm is a lateral stud pin 7. Where this stud pin 7 engages the arm 5, it is constructed rectangular, thereby preventing the stud pin from turning. One 60 end of the stud pin beyond the rectangular part 7 is provided with a cylindrical extension 8 having threads. This extension enters an opening 9 of the up-standing arm 10, and by means of the nut 11 which is 65 threaded on the extension 8, the up-standing arm 10 is held fixedly in position. Mounted upon the pin 7 is a tubular sleeve 12. The other end of the pin 7 enters an opening 14 of the other end of the sleeve. 70 This opening 14 of the sleeve is formed in the reduced end 13 of said sleeve. The reduced end of the sleeve has mounted thereon a drum 16, there being a nut 15 on the outer end of said pin 7 and adapted to jam 75 against the reduced end of said sleeve, thereby holding the sleeve securely in position and against rotation relative to the pin 7. It is to be noted that the drum 16 is capable of a partial spring tensioned 80 revolute movement on the reduced end 13 of the sleeve 12, due to the action of the spring 17. The coil spring 17 has one end passing through the wall of the sleeve at one of its ends and engaged about the pin 85 7. The other end of the spring passes through the wall of the drum 16, and terminates in a hook 18, to which one end of a strap 19 is connected, the other end of the strap is connected to the picker-stick 4 by 90 means of the clamp 20, which is secured in place by means of the bolt 21 and the nuts 22, which bolt 21 also secures the shoe 23 to the lower end of the picker-stick. This shoe 23 rests and rocks upon the upper flat 95 surface of the picker-stick stand 3. The shoe 23 has a lug 24 extending downwardly and through an opening 25 of said stand, which, on its upper face, has a lug 26, which enters the opening 27 of the shoe. Secured 100 in the upper part of the up-standing arm 10 is a reduced extension 28 (rectangular in cross section) of the laterally extending pin 29, by means of the nut 30 and lock nut 31. The pin 29 has a second rectangular 105 portion 32, on which a fiber disk 33 is mounted, between the shoulder 34 and the outer face of the up-standing arm 10. The body of this pin 29 is larger in diameter than the rectangular part or portion 32, 110 and mounted on this larger portion is a wood or fiber disk 35. Carried by the disk

35 is an elongated lever 36 provided with an elongated slot 37. Also mounted upon the larger portion of the pin 29 is a third disk 38, between which and the disk 33, the 5 disk 35 frictionally engages. Secured by a set screw 39 on the pin 29 is a collar 40, between which and said disk 38, a coil spring 41 is interposed, thereby holding the disks 33, 35 and 38 frictionally in contact, 10 in order to offer frictional resistance for the disk 35. The tension of the spring 41 may be increased or decreased by adjusting the collar 40. A screw 42 is mounted in the elongated slot 37 of the lever 36, and there 15 is a collar 43 on the screw adjacent the outer face of said lever 36. A suitable plate 44 is also on the screw 42 and has its ends 45^a bent laterally to overlie the opposite edges of said lever 36, there being a 20 nut 45 threaded on the screw to engage against said plate, in order to draw the head 46 of said screw tight against the end of the extension bushing 47 of said collar 43 thereby holding the parts together. It is 25 to be observed that by loosening the nut 45, the screw 42 may be raised and lowered in the slot 37, so as to support the collar 43 in different adjusted positions. A suitable plate 48 is mounted rockably on the extension bushing 47, and one end of this plate terminates in a bearing sleeve 49, through which the rod 50 extends. A clamping strap 51 engages about one edge and two side faces of the picker-stick 4, and is secured thereto by means of a set screw 52. The ends of the strap receive a transverse bolt 53, on one end of which a pair of nuts 54 and a washer 55 are secured, to draw the 30 ends of the strap 51 together and in engagement with the sleeve or bushing 56, which is mounted upon the bolt 53. One end of the rod 50 is provided with an eye 57 which receives and engages the sleeve or bushing 56. Mounted upon the rod and designed to 35 be held in adjusted positions by the set screws 58 are set collars 59 and 60, there being a spring 61 interposed between the set collar 60 and the bearing sleeve 49.

From the foregoing, in connection with the 40 drawings, it is to be noted that when the loom picks or throws the shuttle (not

shown) by making a rearward stroke, in fact moving the picker-stick 4 in the direction of the arrow *a*, pulling the rod 50 forwardly, making it slide through the sleeve bearing 49, until the set collar 59 will contact with one end of the sleeve bearing, after which the lever 36 is oscillated, and owing to the frictional contact between the disks 33, 35 and 38, frictional resistance is offered, thereby gradually limiting the picker-stick, rather checking the same on its rearward stroke. On the forward stroke of the picker-stick in the direction of the arrow *b*, the collar 60 pushes against the spring 61, which in turn pushes against the bearing sleeve, thereby holding it in contact with the sleeve 49, and owing to the frictional resistance between the disks 33, 35 and 38, the picker-stick is checked in its rearward movement, 55 at the limit of its stroke. Owing to the spring 61, there is a yieldable action between the lever 36 and the picker stick. By virtue of the adjustability of the screw 42 and the adjustability of the straps 51, the checking device may be adjusted according to the 60 stroke of the picker-stick.

The invention having been set forth, what is claimed as new and useful is:

In a device as set forth, a stand having an 65 upstanding arm, frictional resistant means carried by the upper end of said arm and provided with a slotted lever, a sleeve bearing, means for pivotally and adjustably connecting the bearing sleeve to said slotted lever, a rod mounted in the bearing sleeve and having one end pivotally and adjustably connected to the picker-stick, a pair of set collars on the rod, with one of which said bearing sleeve is designed to contact, 70 and a spring interposed between the other set collar and the bearing sleeve, whereby the checking of the picker-stick in its forward and rear movements is effected.

In testimony whereof I have signed my 75 name to this specification in the presence of two subscribing witnesses.

WALTER SIMPSON FINCH.
